UNITED STATES PATENT OFFICE.

FREDERICK DARLINGTON, OF NEW YORK, N. Y., ASSIGNOR TO WESTINGHOUSE ELECTRIC & MANUFACTURING COMPANY, A CORPORATION OF PENNSYLVANIA.

APPARATUS FOR NITROGEN FIXATION.

1,401,678.

Specification of Letters Patent. Patented Dec. 27, 1921.

Application filed November 23, 1917. Serial No. 203,539.

To all whom it may concern:

Be it known that I, FREDERICK DARLINGTON, a citizen of the United States, and a resident of New York city, in the county of New York and State of New York, have invented a new and useful Improvement in Apparatus for Nitrogen Fixation, of which the following is a specification.

My invention relates to apparatus for the fixation of atmospheric nitrogen, and it has for its object to provide a mechanism of the character designated which shall be simple, inexpensive and rugged in construction and highly effective and long-lived in operation.

10 In the accompanying drawing, Figure 1 is a side view, partially in section and partially in elevation, of a rotatable furnace embodying a desirable form of my invention; Figs. 2 and 5 are views similar to Fig. 1 and showing modified forms of furnaces embodying my invention; Figs. 3 and 4 are detail views of portions of the apparatus employed in the furnace of Fig. 2; and Figs. 6 and 7 are detail views illustrating certain portions of the apparatus employed in the furnace of Fig. 5.

Processes for the fixation of atmospheric nitrogen are well known in which a stream of nitrogen-bearing gas is passed over a mixture of carbon and alkali-metal carbonate in the presence of a catalyzing agent, such as iron, which serves to dissolve the carbon and thus break down the structure of the carbon molecules. Processes of this nature are fully set forth and claimed in U. S. Patent No. 1,091,425, issued to the Nitrogen Products Company on March 24, 1914, on an application filed by John E. Bucher.

In the process of the aforementioned Bucher patent, the carbon and alkali-metal carbonate are reduced to a finely divided state, thoroughly mixed, and then placed in a retort, together with an admixture of finely divided iron. A nitrogen-bearing stream of gas being then passed over the mixture, the finely divided iron acts as a catalyst, dissolving a portion of the carbon and reducing it substantially to the nascent state, whereupon the nitrogen combines therewith, forming cyanogen which immediately combines with the alkali metal set free by the reduction of the carbonate by the remainder of the carbon. This operation is very effective, particularly on a small scale, but difficulties are encountered,

at times, in securing the proper relative amounts of nitrogen and of alkali-metal carbonate at each and every point where the reaction is taking place. Thus, if there is an excess of carbonate or if the temperature of the furnace is too high, the carbonate permeates the entire mass of the charge, preventing the entry of nitrogen thereinto and limiting the reaction to the outer surface of the mass. On the other hand, if there is a deficiency of alkali-metal carbonate, or if the temperature of the furnace be slightly too low, the fused carbonate does not penetrate through the mass of iron filings and carbon, and a large portion of the divided material is ineffective.

By the present process, I provide means whereby a mixture of carbonate and carbon is continuously ground and mixed within a heated nitrogen-containing space by a mechanism comprising grinding faces composed wholly or in part of iron. By this means, all portions of the reacting mass are continuously kept in motion and intimately mixed, and, furthermore, carbonized surfaces of iron are continuously being exposed to the nitrogen gas, whereby the reaction may be effected with substantially uniform results, even though there be wide variations in the amounts of the constituent reagents and in the temperature of the furnace.

Referring to the drawing for a more detailed understanding of my invention, I show the barrel of a rotatable or tubular furnace, such as is commonly employed in cement manufacture, at 8, in Fig. 1. Said barrel comprises an outer supporting casting 9 provided with a heat-resistant lining 10 which, in turn, is provided with a lining 11, preferably assuming the form of a plurality of iron rings 12-12, each of which has a peripheral groove in its inner face.

The barrel 8 is mounted for rotation in a sloping position as by being placed upon rollers 13-13 and is driven by any suitable means, such, for example, as a motor 14 operating upon a girth gear 15.

The interior of the barrel 8 may be heated by any suitable means such, for example, as a flame of powdered coal 16, shown as issuing from a nozzle 17, the coal being supplied from a hopper 18 by a screw feed 19 and a suitable air blast being provided as by a blower 20. The products of com-

bustion, after traversing the barrel 8, pass up a suitable flue 21.

5 A charge of alkali-metal carbonate and powdered carbon is placed in a hopper 22 and is supplied to the upper end of the barrel 8, as by a screw feed 23.

In order to supply the interior of the barrel 8 with nitrogen, in addition to that issuing from the nozzle 17, air may be 10 driven by a suitable blower 24 through a mass of incandescent carbon 25 and into the furnace at 26, thus insuring an ample supply of nitrogen for the furtherance of the reaction.

15 In order to intimately grind and mix the charge and, at the same time, to present thereto large and constantly refreshed surfaces of catalytic material, I place balls 27-27 of ferrous material in the respective 20 grooves of the rings 12-12 so that as the barrel 8 is turned by the motor 14, said balls roll in said grooves.

Having thus described an apparatus embodying my invention, the operation is as 25 follows: The heating source 16 is placed in operation and the barrel 8 is rotated until all portions thereof are thoroughly heated. The fan 24 is then started, forcing air through the mass of incandescent carbon at 30 25 and into the furnace. The effect of the carbon at 25 is to change the oxygen of the air into either carbon monoxid or carbon di-oxid, preferably the former. The feed device 23 is then started and the charge is

35 permitted to slowly pass into the furnace, whence it passes from groove to groove until it falls from the barrel 8 into a pocket 28. The rotation of the furnace barrel causes the balls 27 to continually traverse their respective grooves and to thoroughly mix and grind the charge as it slowly passes through the furnace. The temperature is so high that the iron rings 12 and the balls 27 are capable of readily taking up carbon from the 40 charge. Said carbon, when dissolved in iron, is rendered chemically active in its molecular structure and, in this form, readily combines with the nitrogen passing through the furnace and with the sodium 45 formed by the reduction of the sodium carbonate by a portion of the carbon, forming sodium cyanid, which passes through the barrel 8 to the pocket 28, together with such portions of the charge as are not acted upon.

50 The charge collecting in the pocket 28, may be treated for the removal of the sodium cyanid, either by lixiviation or by vacuum distillation, as is desired. The specific process employed for separating the sodium cyanid 55 forms no part of this invention and therefore demands no further discussion.

While I have shown both the tracking surface of the rings 12-12 and the balls 27-27 as formed of iron, it is obvious that similar 60 effect may be produced by forming only one

of the active grinding surfaces from the catalytic material.

Referring to the form of my invention shown in Figs. 2, 3 and 4, an inclined tubular barrel 8 is mounted for rotation as before, said barrel comprising an outer frame or casing 9 provided with a heat-resistant lining 10. Within this lining is a layer 30 of insulating, heat-resistant material such, for example, as mica or asbestos, within 70 which is embedded a heating conductor 31 which is wrapped around the entire length of the tube 8 and terminates in suitable slip rings 32-32 which are connected, in turn, by suitable brushes, to the terminals of a 75 source of heating current such, for example, as the secondary winding 33 of a transformer 34.

Mounted within the layer 30 are a plurality of iron rings 34-34, shown as provided with substantially cylindrical inner surfaces. A plurality of rollers 35-35 are mounted to bear upon the inner surfaces of the rings 34-34 and said members 35 are preferably provided with pronounced helical 90 grooves in their outer faces, as shown. The members 35 are loosely keyed to a shaft 36, as indicated in Fig. 4, and said shaft may be driven by a suitable motor 37, preferably through a universal joint 38. 95

A nitrogen-bearing gas stream is introduced at 26, as in the furnace of Fig. 1, and the charge is similarly supplied from a hopper 22.

In operation, the barrel 8 is first thoroughly heated by causing current to traverse the conductor 31, and the barrel 8, together with the shaft 36, is then caused to revolve, the relative direction of rotation being determined by the direction of pitch of the helical grooves on the members 35-35. The charge slowly passes down through the barrel 8 and is thoroughly mixed and ground by the members 35-35, its rapidity of passage being capable of accurate control by 100 the speed adjustment of the motor 37, so that a given portion of the charge may be subjected to chemical action for so long a period of time as is deemed necessary. 105

In the form of my invention shown in 110 Figs. 5, 6 and 7, a furnace barrel 40 is employed, said barrel preferably comprising an outer casing 9 provided with a heat-resistant lining 10, which, in turn, is provided with a ferrous lining 41, preferably composed of 115 rings 42-42.

A combined heating, grinding and catalyzing structure is shown within the barrel 9 at 43-43 and preferably comprises a plurality of rings 44-44, each of which is 120 preferably disposed to bear upon the inner surface of one of the rings 42-42, respectively. Said rings 44-44 are interconnected by suitable conducting bars 45-45, the 125 conducting bars on one side of a given ring 130

44 preferably being mounted in spaced relation to those on the other side of said ring, as indicated in Figs. 6 and 7. The rings 42-42 are separated by insulating spacer 5 members 55-55 in order to prevent short-circuiting the rings 44-44.

The entire structure 43-43 may be rotated, as by a motor 46 and electric current from a suitable source may be supplied to 10 one end thereof by a brush 47 and taken from the other end thereof by a brush 48. In order to prevent the shunting of current from said device, it may be mounted in insulating bearings, as indicated at 49-49.

15 In operation, current is first passed between the brushes 47 and 48, thoroughly heating the entire structure 43. The charge is then permitted to flow from the hopper 22 and passes down slowly through the barrel 20 40, being continuously mixed and ground by the rings 44 and the bars 45, at the same time being chemically acted upon by said rings and conducting bars which are of ferrous nature and of sufficiently high temperature 25 to act effectively as catalytic members. After traversing the barrel 40, the resultant products are received at 28, as before.

30 In the apparatus of Fig. 5, I have shown the nitrogen as flowing from a tank 50, it sometimes being desirable to employ substantially pure nitrogen. The excess of nitrogen may be carried away by a pipe 51 and suitably purified for return to the system.

35 While I have shown my invention in three of its preferred forms, I desire it to be distinctly understood that I am not restricted thereto but that I may modify any or all of the structures shown in many particulars as by interchanging features thereof and by 40 modifying features of one apparatus in a manner similar to that mentioned for another form of the apparatus.

I desire, therefore, that only such restrictions shall be placed upon the present invention as are imposed by the prior art or are 45 specifically set forth in the appended claims.

I claim as my invention:

1. In a furnace for the carrying out of a chemical reaction involving the action of a 50 catalytic agent upon a mass of material, a mixing device for said material formed, in part at least, from said catalytic agent, whereby substantially all portions of said mass are periodically subjected to the action 55 of said catalytic agent.

2. In a furnace for the carrying out of a chemical reaction involving the action of a catalytic agent upon finely divided material, a grinding mechanism having a portion of 60 its grinding faces formed of said catalytic agent and arranged to operate upon said treated material.

3. In a furnace for the carrying out of a chemical reaction involving the action of 65 iron as a catalytic agent upon a mass of

material, a stirring device for said mass formed, in part at least, of iron.

4. In a furnace for the carrying out of a chemical reaction involving the catalytic action of iron upon a mass of finely divided 70 material, a grinding mechanism for said material, a portion of the grinding faces of which are composed of iron.

5. In a rotatable furnace for the carrying out of a chemical reaction involving the action of a catalytic agent upon a mass of finely divided material, a rotatable body disposed against the inner wall of said furnace, whereby, when said furnace is rotated, a pulverizing action is exerted upon said 75 finely divided material, at least one of the two coactive pulverizing surfaces being faced with said catalytic agent.

6. In a rotatable furnace for the carrying out of a chemical reaction involving the 80 catalytic action of iron upon a mass of finely divided material, a rotatable body disposed against the inner side of the wall of said furnace, whereby, when said furnace is rotated, a pulverizing action is exerted upon 85 said finely divided material, at least one of the two coacting pulverizing surfaces being faced with iron.

7. In a rotatable furnace for the carrying out of a chemical reaction involving the 90 action of a catalytic agent upon a mass of finely divided material, a rotatable body formed of said catalytic agent and disposed against the inner wall of said furnace, whereby, when said furnace is rotated, a 95 pulverizing action is exerted upon said finely divided material and the catalytic agent composing said rotatable body is brought into intimate contact with all portions of said finely divided mass. 100

8. In a rotatable furnace for the carrying out of a chemical reaction involving the catalytic action of iron upon a mass of finely divided material, a rotatable body of iron disposed against the inner side of the 110 wall of said furnace, whereby, when said furnace is rotated, a pulverizing action is exerted upon said finely divided material and the surface of said iron body is brought into intimate contact with all portions of 115 the charge.

9. In a rotatable furnace for the carrying out of a chemical reaction involving the action of a catalytic agent upon a mass of finely divided material, a rotatable body 120 disposed against the inner face of the wall of said furnace, whereby, when said furnace is rotated, a pulverizing action is exerted upon said finely divided material, the tracking surface containing an appreciable 125 amount of said catalytic agent.

10. In a rotatable furnace for the carrying out of a chemical reaction involving the catalytic action of iron upon a mass of finely divided material, a rotatable body disposed 130

against the inner side of the wall of said furnace, whereby, when said furnace is rotated, a pulverizing action is exerted upon said finely divided material, the material of 5 the tracking surface including an appreciable amount of iron.

11. In a rotatable furnace for the carrying out of a chemical reaction involving the action of a catalytic agent upon a mass of 10 finely divided material, a rotatable body formed from said catalytic agent and disposed against the inner wall of said furnace, whereby, when said furnace is rotated, a pulverizing action is exerted upon said 15 finely divided material, the tracking surface containing an appreciable amount of said catalytic agent.

12. In a rotatable furnace for the carrying out of a chemical reaction involving the 20 catalytic action of iron upon a mass of finely divided material, a rotatable body of iron disposed against the inner side of the wall of said furnace, whereby, when said furnace is rotated, a pulverizing action is exerted 25 upon said finely divided material, the material of the tracking surface including an appreciable amount of iron.

13. The combination with a furnace for the production of cyanid compounds of a 30 metal by the action of carbon and nitrogen upon a salt of said metal, of a grinding and mixing mechanism adapted to operate upon the charge and composed, in part, at least, of a material which operates as a 35 catalyst in assisting the reaction.

14. The combination with a furnace for the production of cyanid compounds of one of the alkali metals by the action of nitrogen and carbon upon the carbonate of said 40 alkali metal, of a mixing and grinding mechanism adapted to operate upon said charge and having a portion of the active

face thereof composed of iron, whereby the carbon is continually dissolved in said iron and thereupon combines with the nitrogen. 45

15. In a furnace for the carrying out of a chemical reaction involving the action of iron as a catalytic agent upon a mass of material, a stirring device for said mass formed, in part at least, of iron, and means for developing heat electrically within said furnace and in immediate proximity to said mass.

16. In a furnace for the carrying out of a chemical reaction involving the action of 55 iron as a catalytic agent upon a mass of material, a stirring device for said mass formed, in part, at least, of iron, and means for passing heating current through said stirring device.

17. In a furnace for the carrying out of a chemical reaction involving the catalytic action of iron upon a mass of finely divided material, a grinding mechanism for said material, a portion of the grinding faces of 65 which are composed of iron, and means for passing heating current through said grinding mechanism, whereby heat is developed in immediate proximity to the seat of the chemical reaction.

18. The combination with a furnace for the production of cyanid compounds of a metal by the action of carbon and nitrogen upon a salt of said metal, of a grinding and mixing mechanism adapted to operate upon 75 the charge and composed, in part at least, of a material which operates as a catalyst in assisting the reaction, and means for passing heating current through said grinding and mixing mechanism.

In testimony whereof, I have hereunto subscribed my name this 8th day of November, 1917.

FREDERICK DARLINGTON.
